STARR POLLEY, OF BROOKLYN, NEW YORK, ASSIGNOR TO AMBROSE HILL, OF SAME PLACE.

Letters Patent No. 63,173, dated March 26, 1867.

IMPROVEMENT IN ROUNDING-JACKS FOR TRIMMING BRIMS OF HATS.

The Schedule referred to in these Letters Patent and making part of the same.

TO ALL WHOM IT MAY CONCERN:

Be it known that I, STARR POLLEY, of the city of Brooklyn, county of Kings, and State of New York, have invented certain new and useful Improvements in the Means for Trimming the Edges of the Brims of Hats; and I do hereby declare that the following is a full and exact description thereof.

My invention allows the cutting tools to be adjusted with great facility, both in regard to the breadth of the brim, and the depth to which the cutter shall project. It also provides against a possibility of cutting the board or support on which the brim rests.

I will first describe what I consider the best means of carrying out my invention, and will afterwards designate the points which I believe to be new. The accompanying drawings form a part of this specification.

Figure 2 is a vertical section through the instrument on the line S S in fig. 2.

Figure 1 is a plan view of the instrument in position for use.

Figure 2 is in the reverse of the position in which the instrument is commonly used.

Similar letters of reference indicate like parts in both figures. Tints are employed merely to aid in distinguishing parts, and do not indicate differences in material. The metal portions may be of iron and steel. The body of the instrument may be of wood.

A is a curved portion of the frame, adapted to apply against the side of the crown of a hat of any ordinary size, and to fit against the same with approximate accuracy. This part has also parallel ways, A 1 A 2, fixed theron, so well known to hatters they need not be particularly described. B is a sliding-block, mounted on the ways, and adapted to be moved outward and inward, according as the brim is to be broader or narrower. It carries a cutter, b, of steel, which projects downwards beyond the lower surface of the block B, in the manner represented, and is properly bevelled, to cut smoothly and accurately around the brim as the entire tool is traversed along, or as the hat may be traversed under it, according as either motion may be preferred by the operator. C is an adjusting-screw, tapped through the head b 1 of the cutter b. This screw is supported near each end in bearings in piece M, which is carried on the block B, as represented, so that, as the screw C is turned in one direction or the other, the cutter b is raised and lowered so as to graduate the depth of the cut. D is a screw, formed and arranged as represented, which secures the piece M, and consequently the screw C and cutter b, in the proper position in the sliding-block B. By removing this screw D the parts described may be easily removed to allow of repairs. E is an elastic plate of steel or other suitable material, arranged as represented, and secured across the outer ends of the ways A 1 A 2 by means of the screws E 1 E 2, as represented. This plate is thin and smooth, and is adapted to lie under the hat brim, and to be traversed around as the instrument is operated. It forms a shield or guard to prevent the cutter b from passing beyond the lower surface of the brim under any circumstances. Its elasticity is sufficient to allow it to rise into the position indicated by the red lines in fig. 1 when it is in use. G is an adjusting-screw, tapped through the sliding-block B, and supported in the framing in the manner represented, so that, by turning the screw G, the block B and its connections may be traversed outward or inward with great facility, and may be adjusted in any position desired with great accuracy.

My invention avoids an evil which has been long experienced in large manufactories of hats, to wit, the mutilation and rapid destruction of the support on which the hat is laid when the brim is cut. It accomplishes this end by virtue both of the means for adjusting the depth to which the knife B may project, so that it shall be graduated to the thickness of the brim to be cut, and of the guard E, which stands in such position as to form a complete bar against any possible cutting of the support in case of maladjustment of the knife, or in case of the occasional operating on a brim which is thinner than was anticipated. The several additional adjustments also allow the instrument to be put in condition for all the exigencies which arise in practice with less labor and with more exactness than the ordinary instrument. The thin shield E may, if preferred, be hinged at the juncture with the other parts, so as to allow it to more readily stand off from and approach to the face of the instrument; but I do not consider such hinge to be necessary. It will yield sufficiently by its elasticity if proper care be taken in its construction.

Having now fully described my invention, what I claim as new therein, and desire to secure by Letters Patent, is as follows:

1. The cutter *b*, the head *b* 1, adjusting-screw *C*, removable bearings *M*, and confining means *D*, combined and arranged for joint operation on the sliding-block *B* of the brim-cutting instrument, substantially in the manner and for the purpose herein set forth.
2. I claim the radial adjusting-screw *G*, arranged to operate relatively to the sliding-block *B*, and adjustable cutter *b*, in the brim-cutting instrument, substantially in the manner and for the purpose herein set forth.
3. I claim the shield *E*, arranged in combination with the brim-cutter, and adapted to serve relatively to the adjustable cutter *b*, substantially in the manner and for the purpose herein set forth.

STARR POLLEY.
